UNITED STATES PATENT OFFICE.

GUSTAV EY, OF NEW YORK, N. Y.

BLOCK MOLD.

Application filed December 9, 1922. Serial No. 605,902.

To all whom it may concern:

Be it known that I, GUSTAV EY, a citizen of the United States, and a resident of the city of New York, borough of Manhattan, 5 in the county and State of New York, have invented new and useful Improvements in Block Molds, of which the following is a full, clear, and exact description.

This invention relates to block molds and 10 was primarily designed for use in making concrete blocks.

In molds constructed with miter joints a great deal of difficulty is experienced in fitting the molds together after they have been 15 used for some time due to the fact that a certain amount of concrete or the like adheres to the molds. If the molds with miter joints are fitted together with concrete adhering to them the members are likely to be 20 thrown out of proper alignment and the result will be blocks that are not accurately shaped. Other types of molds are constructed and the transverse members are attached to the longitudinal members by fitting a plate on one into a slot formed in the other. This construction is also unsatisfactory because the slots are continually blocked by the concrete.

The general object of this invention is the 30 provision of a simple and efficient mold so constructed that the members may be quickly assembled and disassembled.

A further object of the invention is the provision of a mold, the members of which 35 are provided with simple means for connecting them together, the connecting means being so constructed that the deposits of concrete or the like do not cause any great amount of trouble or the possibility of disalignment resulting in improperly shaped blocks.

Another object of the invention is the provision of a mold, the members of which are formed with straight sides thus introducing cheapness of manufacture and simplifying the replacement of worn and destroyed parts.

These objects are accomplished by constructing from sheet material longitudinal 50 members having hollow longitudinal beadings with straight sides, transverse members provided with hollow straight-sided beadings extending longitudinally of the transverse members, forming notches in the ends of 55 the transverse members for fitting over the beadings on the longitudinal members,

mounting on the beadings of the longitudinal members guides for projecting into the tubular member formed by the beadings of the transverse members, and locating in each 60 section formed by the longitudinal and transverse members means for fixing the depth of the block.

These and other objects of the invention will be more clearly understood from the 65 following detailed description and accompanying drawings.

Figure 1 is a top plan view of a portion of the mold assembled;

Figure 2 is a vertical section along the 70 line 2—2, Figure 1, showing a cross section of the longitudinal member and a side elevation of a transverse member;

Figure 3 is a section along the line 3—3, Figure 1, showing sections of the transverse 75 members;

Figure 4 is a perspective view of a section from which the longitudinal members are constructed;

Figure 5 is a perspective view of an end 80 transverse member;

Figure 6 is a perspective view of one of the sections from which the transverse members are constructed;

Figure 7 is a perspective view of a block 85 that may be formed in the mold.

Referring to the above-mentioned drawings, the invention includes end longitudinal members 10, central longitudinal members 11, end transverse members 12 90 and central transverse members 13. Each end longitudinal member 10 consists of a plate 14 in which a beading or rib 15 is stamped, the beading having straight sides as shown in the figures. A plate 16 is 95 mounted on the back of the plate 14 and is welded thereto, forming a side longitudinal member, as shown in Figures 1 and 3. The central longitudinal members 11 are formed by abutting two of the plates 14 with the beadings 15 extending outward. These plates 14 are then attached together by any means such as welding, thus forming a unit.

The end transverse members consist of 105 a plate 17 in which a beading or rib 18 is formed. This beading or rib 18 is hollow and has straight sides, as shown in Figure 6. Notches 20 are cut in the plate and so shaped that they will fit over the 110 beading 15 of the longitudinal members 10 and 11. A plate 19 having notches 21 cut

in its ends is mounted on the back of the plate 17 and is welded thereto thus forming a unit which serves as an end transverse member. In forming a central transverse member 13, two plates 17 are placed back to back and welded together thus forming a unit with a channel extending the length of it and being equal in width to twice the depth of the beading.

19 The beadings 15 of the longitudinal members and 18 of the transverse members each have vertical front walls 22 and inclined side walls 23 which slope toward the front wall from the base. Mounted on the front wall 22 of the beading 15 of the longitudinal members 10 and 11 are guides 24. These guides are welded to the front wall. The guides 24 are formed from a plate which is bent to form a base 25, two side members 26 extending at right angles to the base 25, and two inclined members 27 which slope inward as shown in Figures 1 and 4. The base 25 is placed parallel to the wall 22 and welded thereto. The length 23 of each guide 24 except the one mounted on the longitudinal members is equal to the inside measurement across the channel formed by the beadings 18 of the central transverse members 13. The guides 24 mounted on the ends of the longitudinal members are smaller in size than the others so that they will fit into the channel formed by the beading 18 of each of the end transverse members. The guides 24 are spaced apart any desired distance, depending on the size of the block it is desired to mold.

40 Frames 29 are provided for carrying the plaques 30. These plaques are provided for mounting on the bottom of each section of the mold for supporting the concrete and giving it a straight face. The area of the plaque 30 is equal to the area of a side of the block it is desired to mold.

45 In assembling the mold, a side longitudinal member 10 is placed against a wall. An end transverse member is then placed in position, the channel formed by the plate 19 and the beading 18 being projected over the end of a guide 24 mounted on the beading 15 of the side longitudinal member. A plaque 30 is then mounted in position, projecting under the beadings of the end transverse member and the longitudinal member. A central transverse member 13 is then placed in position, the guide 24 fitting into the channel formed by the beadings 18. Another plaque is placed in position on the other side of the central transverse member 13. After any desired number of transverse members have been placed in position, a central longitudinal member 11 is placed parallel to the end longitudinal member 10 and the guides 24 projected into the channels in the transverse members. Thus between each pair of transverse

members located between the longitudinal members a mold is formed for a complete block. The depth of the block will depend on the height a plaque 30 is supported from the foundation on which the mold is assembled.

70 After the mixture from which the blocks are to be formed is placed in the mold the upper surface is smoothed off by means of a trowel or any other suitable tool. If concrete adheres to any of the members it is easily removed since it only can attach to straight outside walls.

75 I would state in conclusion that while the illustrated example constitutes a practical embodiment of my invention I do not limit myself strictly to the exact details herein illustrated since manifestly the same can be considerably varied without departing 80 from the spirit of the invention as defined in the appended claims.

Claims:

1. In a concrete block mold, longitudinal members having longitudinal straight-sided beads formed thereon, the inner walls of said beads lying in planes parallel to the longitudinal members, transverse members for mounting between the longitudinal members to form a plurality of separated mold sections, said transverse members having longitudinal beads formed thereon the opposite ends of which terminate in a plane at right angles thereto and in a plane parallel to the inner walls of the beads of the longitudinal members, whereby to permit of abutting engagement of the beads of the transverse members with the inner walls of the beads of the longitudinal members, and means mounted on the longitudinal members for engaging the transverse members to prevent movement of the latter.

100 2. A concrete block mold, comprising longitudinal members having longitudinal straight-sided beads formed thereon, said beads presenting vertical inner walls, transverse members for mounting between the longitudinal members to form a plurality of separated mold sections, said transverse sections having longitudinal beads formed thereon, of a height not exceeding the height 105 of the vertical inner wall of the beads of the longitudinal members, the ends of said beads terminating in a vertical plane parallel to the vertical inner walls of the beads of the longitudinal members, permitting them to be fitted tightly against the vertical walls of the beads on the longitudinal members, means mounted on the longitudinal members for engaging the transverse members to prevent movement of the latter lengthwise of the longitudinal members, and pallets for mounting in each section.

110 3. A concrete block mold, comprising longitudinal members having longitudinal straight-sided beads formed thereon, said 115

straight-sided beads presenting vertical inner walls, transverse members for mounting between the longitudinal members to form a plurality of separated mold sections, said 5 transverse members having longitudinal beads formed thereon, the base of said latter beads being of a height not exceeding the height of the inner walls of the beads of the longitudinal members, the ends of the beads 10 of the transverse members terminating in vertical planes, permitting them to abut against the vertical walls of the beads formed on the longitudinal members, and means mounted on the beads of the longitudinal members for engaging the beads transverse members to prevent movement of the latter members lengthwise of the longitudinal members.

4. A concrete block mold, comprising longitudinal members having longitudinal straight-sided beads formed thereon, presenting vertical inner walls, transverse mem- 15 bers for mounting between the longitudinal members to form a plurality of separated mold sections, said transverse members having notched ends for fitting over the beads formed on the longitudinal members and longitudinal beads formed on said transverse members, said beads being of a height not exceeding the height of the inner walls of the beads of the longitudinal members and terminating in vertical planes parallel to the beads of the longitudinal members whereby to permit the beads on the transverse members to abut against the vertical walls of the beads on the longitudinal members, and means mounted on the longitudinal members for engaging the transverse members, to prevent relative movement between the transverse members 20 and longitudinal members in a longitudinal direction with respect to the longitudinal members.

GUSTAV EY.
